UNITED STATES PATENT OFFICE.

NELSON E. ALLEN, OF FOX LAKE, WISCONSIN, ASSIGNOR TO HIMSELF
AND CHAS. B. WARREN, OF SAME PLACE.

IMPROVEMENT IN SEEDING-MACHINES.

Specification forming part of Letters Patent No. 38,528, dated May 12, 1863.

To all whom it may concern:

Be it known that I, NELSON E. ALLEN, of Fox Lake, in the county of Dodge and State of Wisconsin, have invented a new and Improved Seeding-Machine, Corn-Planter, and Horse-Rake Combined; and I do hereby declare that the following is a full, clear, and exact description of the same, reference being had to the accompanying drawings, making a part of this specification, in which—

Figure 1 represents a sectional elevation of my machine (the section being taken in the line $x x$ of Fig. 5) adapted to sow seed broadcast. Fig. 2 represents a sectional elevation of that part necessary to convert the machine into a corn-planter. Fig. 3 is a rear end elevation of Fig. 2. Fig. 4 is a side elevation of the machine converted into a horse-rake. Fig. 5 is a rear end elevation of Fig. 4. Fig. 6 is a front elevation of a measuring-cylinder and grain-conveying tube on an enlarged scale.

Similar letters of reference indicate corresponding parts in the several figures.

This invention consists, first, in the spiral form given to the cups or receptacles in the seeding-cylinders, in combination with the opening in the caps, whereby the grain, as the cylinders revolve, is deposited onto the ground in a continuous stream; second, in a fluted cone or scatterer capable of being adjusted so as to adapt the machine to scatter over a greater or less area of ground at once; third, in the peculiar manner of attaching the cultivator-bars to the frame of the machine, whereby the driver is enabled to raise the back end of either one of the bars, and consequently its cultivator-tooth, independently of the others, for the purpose of passing over an obstruction, by simply depressing the front end of the bar with one of his feet.

To enable others skilled in the art to fully understand and use my invention, I will proceed to describe its construction and operation.

In Figs. 1, 4, and 5, A represents a rectangular frame, which is mounted on two wheels, B B', and has a box, C, placed on it extending its whole width. Within the box C there is placed a shaft, D, which has a pinion, a, (shown in Fig. 5,) fitted on one end and adapted to be slid longitudinally thereon by means of a le-

ver, b, and thus to be thrown into or out of gear with a wheel, a', attached concentrically to the wheel B.

On the shaft D there is secured a series of hubs, which may be described as being cylinders E, provided with radial spiral flanges c, the spaces between which form seed cups or pockets. Each cylinder E has a shell or hollow cylinder, F, fitted on it. These shells or cylinders F are provided with spiral slots to receive the flanges of the cylinders E, the parts of the shells between the slots fitting snugly in the spaces between the flanges c of the cylinders, and which constitute the seed cups or pockets. The spiral form of the flanges acts to scrape the grain passing through the openings in the caps diagonally or cornerwise, so that before one cup has passed the opening the preceding cup is being filled. In this manner a continuous discharge of grain is kept up between the hopper and the caps, whence it runs in a continuous stream into the ground.

The cylinders F are each provided on their outer ends with a flange, d, and these flanges are clasped by forked projections e on the bar G, which is moved longitudinally within the box C by means of a lever, H. The pendent tubes I², which convey the grain from the sowers to the scatterers, terminate at their upper ends in semi-boxes f, which, together with caps g, inclose the cylinders and thereby preclude the possibility of grain escaping over the sides. Each of the caps g has an oblong opening in it through which the grain passes from the hopper into the cups or pockets in the cylinders.

Directly over the box C there is placed a seed box or hopper, I, the bottom of which is perforated immediately over the cylinders on shaft D. Inside the hopper sunken cavities or depressions are formed in the bottom immediately surrounding the perforations.

In the lower end of each conveying-tube I² there is suspended a fluted cone, J, for the purpose of scattering grain broadcast. This fluted cone J is attached to the tube by a bent arm or bracket, h, which passes upon the outside of the tube and has a set-screw, i, passing through it into the tube. The bracket being slotted where the screw passes through it allows the cone to be adjusted higher or lower.

to adapt the machine to scatter over a greater or less area of ground at once, as may be desired, the grooves or flutes in the cone acting to prevent the grain from being drifted or scattered more on one side than another.

The cultivator-teeth *j* are attached by standards *k* and braces *k'* to bars *K*, which are loosely fitted on shaft *l* and kept at equal distances apart thereon by hubs projecting from opposite sides of the bars. The shaft *l* is unsupported at its ends in boxes or hangers *m*, depending from the side pieces of the main frame *A*. The bars *K* extend in front a sufficient distance to enable the driver, (who sits on the hopper,) by depressing the front end with his feet, to raise any one of the teeth independently of any other for the purpose of allowing that particular tooth to pass over an obstruction or to release it of any rubbish which may have accumulated upon it. The bars *K*, and consequently the cultivator-teeth *j*, are raised or lowered simultaneously by means of the lever *n* and rock-shaft *L*, from which latter they are suspended at their rear ends by cords or chains *o*. The rock-shaft *L* rests at its ends in bearings in the side pieces, *A' A'*, of the frame *A*, and when turned so as to elevate the cultivator-teeth to their highest position is, together with the latter, retained in such position by inserting a pin in one of the holes in the post *p* above the lever.

To adapt the machine to use as a horse-rake the cultivator-bars *K* and the device for elevating the same have both to be removed, and in place of the latter put the rake-shaft *M*. This shaft *M* has secured upon it in the middle a cam-wheel, *N*, and on each side thereof is furnished with any proper number of wire teeth, *q*, and on one end is provided with a pulley, *O*, by means of which and a band it is rotated by one of the driving-wheels, as will be presently explained. The rear end of the lever *P*, which has its fulcrum at *r* in the post *p*, rests on the periphery of or rides the cam-wheel *N* and is kept in close contact therewith by a spring acting through the bell-crank shaft. The front of the lever *P* terminates in a fork embracing the bent arm *s* of bell-crank shaft *Q*. This bell-crank *Q* rests at its ends in suitable bearings, and to its arm *t*, Fig. 1, is pivoted a rod, *u*, which extends to and is connected with the semi-clutch *R*, that can freely move on the axle until forced by a hand-lever, *S*, into gear with another semi-clutch, *T*, formed on the hub of the driving-wheel *B*, and these two parts, forming a regular clutch, must rotate together until released.

On the semi-clutch *R* there is a pulley, *U*, around which and around pulley *O* on the rake-shaft passes an endless belt, *v*, for revolving the rake, imparting to it a positive movement.

The tongue *V*, to which the team is hitched, is pivoted to the front end of the frame, and has a lever, *w*, rigidly attached to its upper side. This lever *w* extends backward and upward through a mortise in a curved arm, *X*, and is for the purpose of raising or lowering

the hind part of the machine, and with it the rake, by depressing the forward end of the machine.

When properly adjusted, either for raking hay or for transporting to or from the field, the rake is retained in such position by a pin put through one of the series of holes in the curved arm and through the lever.

The operation of the rake is as follows: The parts being in the position shown in Figs. 4 and 5—that is to say, with the rake-shaft locked and clutch thrown out of gear—the driver causes the horse or horses to move on until a sufficient distance is passed over to form a windrow. He then takes hold of the lever *S* with one hand and pushes it toward the right-hand side of the machine. This throws the rear end of the lever *P* out of the depression in the cam-wheel, and simultaneously therewith throws the half-clutches into gear, and, the machine still moving, the driving-wheel, through the clutch-pulleys and belt, immediately rotates the rake backward, leaving the hay in a windrow. As soon as the rake commences to revolve the driver removes his hand, and the spring *S'*, which was compressed by the movement of the lever *S*, turning the bell-crank lever, throws it up, unlocking the clutch and forcing the end of the lever *P* into or against the shoulder on the cam-wheel when it comes round, which locks the rake until another windrow is formed, and then another similar operation is gone through with, and so on.

To adapt the machine to use as a corn-planter the horse-rake has to be removed, and in its place put the shaft shown in Figs. 2 and 3. The board *W*, which has hoppers *y y* attached to its upper side, and the board *X'*, which has pendent drill-tubes *2* and coverers attached to its under side, are then placed on the top and bottom sides respectively of the side pieces, *A'*, of the frame *A*, and firmly secured by the bolts passing through them. Immediately under the hoppers *y*, and over the pendent drill-tubes *2*, cylinders *3* are secured on the shaft *M'*. These cylinders *3* have formed in their peripheries depressions or cavities which measure the quantity of seed deposited in the drills. An aperture is made through the board *W* corresponding in size with the bottom of the hoppers *y*, and a flange, *4*, which is of circular form and attached to the upper side of the board *X'*, incloses the front side of the seed-cylinder *3*, and prevents the seed which is in the cups in the periphery of the cylinder from escaping until opposite the mouth of the drill-tube *2*, whence it is deposited into the ground. Each of the coverers is formed with two outwardly-flaring blades, *5 5*, which are so arranged behind the drill-tubes as to throw the dirt from each side thereof into a ridge which is flattened by a roller, *6*, journalized in the lower ends of the standards of the blades *5*, and immediately behind them. The raising or lowering of the drill-tubes to vary the depth thereof in the

ground, or for any other purpose, being effected in precisely the same manner and by the same means as the raising or lowering of the rake, the description of the latter will answer the former.

Having thus described my invention, what I claim as new, and desire to secure by Letters Patent, is—

1. The spirally-formed cups or pockets in the cylinders E, in combination with oblique openings in the stationary caps g, arranged to operate in the manner and for the purpose specified.

2. The fluted cone or scatterer J, attached

to the tube l² by an arm, h, and screw i, so that it can be adjusted within the lower end of the tube, as and for the purposes specified.

3. Suspending the bars K, to which the cultivator-teeth j are attached, from shaft l, so as to have them project a sufficient distance in front of the shaft to form pedals, by which either one of the cultivator-teeth may be raised independently of the other, in the manner specified.

NELSON E. ALLEN.
